(57) **CLAIM**

I claim the ornamental design for surgical headband, as shown and described.

DESCRIPTION

The claimed headband is for being worn by a surgeon during surgery.

FIG. 1 is a top plan view of a surgical headband showing my new design;

FIG. 2 is a bottom plan view thereof;

FIG. 3 is a front elevational view thereof;

FIG. 4 is a rear elevational view thereof;

FIG. 5 is a right side elevational view thereof; and,

FIG. 6 is a left side elevational view thereof.
